UNITED STATES PATENT OFFICE.

ROBERT WEIDEN, OF NEW YORK, N. Y.

DESIGN FOR GIMP.

SPECIFICATION forming part of Design No. 12,919, dated May 2, 1882.

Application filed March 18, 1882. Term of patent 3½ years.

To all whom it may concern:

Be it known that I, ROBERT WEIDEN, a citizen of the United States, residing at the city of New York, in the county and State of New York, have invented and produced a new and original Design for Gimp for Trimming Furniture and for other Purposes, of which the following is a specification, reference being had to the accompanying drawing, forming a part thereof, in which the figure is a front elevation, illustrating my newly-designed gimp.

The leading feature of my design consists in weaving the gimp in such manner or with such variation of colors that the same will present in front elevation somewhat the appearance of a fringe. The general appearance of the gimp consists of parallel bars with a border above, interspersed with shorter bars, this border being surmounted by another border, preferably in the form of scallops; and this general appearance also constitutes a part of my design.

In the drawing, *a* represents bars which are of one color, and *b* bars parallel therewith of another color, which alternate the bars *a*; and *c* is the upper mixed border, which may or may not be, but is by preference, interspersed with the short bars *d*, of a different color from that of the mixed border; and *e* represents the outer border or edging, which

is by preference formed of the scallops *f* and the longitudinal cords *g g*. Upon the opposite edge of the gimp are formed the scallops *h*. Thus formed, it will be seen that the gimp in front elevation will present to the eye the general appearance of a fringe. 35

It will be understood that the colors may be selected and variously combined to suit the taste and the purpose for which the gimp is to be used. 40

Having thus fully described my invention, I claim as new and desire to secure by Design Patent—

1. The design for gimp herein shown and described, the same consisting of suitable parallel bars *a b* and a border, *c*, whereby the gimp will have the general appearance of a fringe, as specified. 45

2. The design for gimp herein shown and described, the same consisting of the parallel bars *a b*, mixed border *c*, interspersed with the bars *d*, and the edging *e*. 50

3. The design for gimp herein shown and described, the same consisting of the parallel bars *a b*, and mixed border *c*, interspersed with the bars *d* and edged with the scallops *f and h*. 55

ROBERT WEIDEN.
